CLAIM

The ornamental design for a bucket lid, as shown and described.

DESCRIPTION

FIG. 1 is a front perspective view of a bucket lid showing our new design placed on a bucket;

FIG. 2 is a side elevation view of the bucket lid without a bucket showing a first buckle;

FIG. 3 is a side elevation view of the bucket lid without a bucket showing a second buckle;

FIG. 4 is side elevation view of the bucket lid without a bucket showing both buckles;

FIG. 5 is a side elevation view of the bucket lid without a bucket showing both buckles from the opposite side as in FIG. 4.

FIG. 6 is a bottom plan view of the bucket lid without a bucket;

FIG. 7 is a top plan view of the bucket lid with a bucket lip illustrated in broken lines; and,

FIG. 8 is a side elevation view of the bucket lid without a bucket showing a buckle with the bottom side facing upward.

The rounded broken lines shown in FIG. 1 depicting a bucket, straps extending to a rod, and the rod represent environmental subject matter that forms no part of the claimed design. The square broken lines shown in FIGS. 1-8 depicting the stitching does form a part of the claimed design for the present patent application.
